UNITED STATES PATENT OFFICE.

PETER E. SMITH, OF PHILADELPHIA, PENNSYLVANIA.

UNDERFEED STOKER.

Application filed February 21, 1922. Serial No. 538,244.

To all whom it may concern:

Be it known that I, PETER E. SMITH, a citizen of the United States, residing in Philadelphia, Pennsylvania, have invented Underfeed Stokers, of which the following is a specification.

One object of this invention is to provide a stoker of the single retort, center-underfeed type, with novel means for delivering air under pressure and feeding the fuel, the arrangement and proportions of the parts being such that said fuel shall be completely consumed with a minimum of air.

Another object of the invention is to provide a stoker of the above type including tuyère plates of such design that interference with the operation of the stoker by siftings through said plates or between the tuyère boxes shall be practically eliminated and in which the frictional resistance to the movement of the tuyère plates shall be reduced to a minimum.

I further desire to provide a stoker with novel means whereby the volume and pressure of the air delivered may be adjusted at will to most efficiently burn the fuel and in which the loss of heat due to excess of air shall be reduced to a minimum;—the construction being such as to effectually prevent such flow of air as will cause burning out of the tuyère plates or their supporting structures.

I also desire to provide an underfeed stoker with a novel arrangement of parts for causing air from a source to be delivered under high pressure to certain portions of said stoker and under relatively lower pressure to other parts thereof, the invention contemplating novel means whereby the supply of low pressure air may be conveniently governed.

Another object of my invention is to provide a stoker of the above noted type having such an arrangement of parts as will insure a minimum of repairs and facilitate removal of ashes and refuse;—the device more especially including tuyère plates of novel form and mounting, in combination with novel means for supporting and actuating said plates.

These objects and other advantageous ends I attain as hereinafter set forth, reference being had to the accompanying drawings, in which,

Fig. 1 is a diagrammatic plan of a stoker 55 constructed in accordance with my invention;

Fig. 2 is a transverse vertical section on the line 2—2, Fig. 1;

Fig. 3 is a plan on a larger scale than 60 Figs. 1 and 2, illustrating the detail construction of one of the tuyère plates and of the supporting structure for an adjacent plate;

Fig. 4 is a vertical section on the line 4—4, 65 Fig. 3; and

Fig. 5 is a transverse section on the line 5—5, Fig. 4.

In the above drawings, 2 represents a suitable foundation on which is built the 70 setting 1 for the boiler to which my invention is to be applied. This setting encloses or defines a chamber substantially rectangular in horizontal section and has extending across it a horizontal retort 3 to which fuel 75 is supplied by any suitable means. From this retort said fuel is delivered laterally in opposite directions over two series of tuyère plates hereafter described in detail.

Immediately under said retort and like it 80 extending transversely between opposite walls of the setting, is a chamber 4 supplied with air under pressure from a suitable blower or compressor, and this chamber is defined by a pair of parallel walls 5 projecting upwardly from the foundation 2. Each of these walls carries or includes vertical partition members 6 extending to a height slightly below the top of the retort 3 and like said walls 5, running from one side to the 85 other of the setting.

Between each of the partitions 6 and the side walls 1 of the setting and parallel thereto is mounted a beam or girder 7 serving to support the lower ends of a series of parallel hollow frames 8 of angular cross section, whose upper ends are supported in any suitable manner, in the present instance upon one of the longitudinal edges of the retort 3, so that they extend substantially at 90 right angles to the latter. There is thus a series of frames on each side of said stoker and the individual frames fit together as indicated in Fig. 5 so as to form a series of elongated, open topped tuyère boxes 9 extending outwardly from the retort 3 toward the side walls 1.

At the lower end of each of the frames

8 is a flat-topped projecting ledge 10 and between the line of these ledges and the adjacent wall 5 is mounted a series of dumping plates 11, preferably carried upon and fixed 5 to a shaft 12 rotatably mounted in the end walls 1^a and operable by any suitable means (not shown) for the purpose of permitting said plates to swing downwardly and dump into the ash pit 13 under them the ashes 10 which may have accumulated thereon.

Adjacent the upper end of each of the tuyère boxes formed by the frames 8 is a transverse, substantially vertical partition 14 near which there is formed in the bottom 15 of each frame an opening 15 communicating directly with the air chamber 4. The flow of air through these openings 15 into the several tuyère boxes is controlled by a grid or sliding valve plate 16 mounted in suitable guideways on the frames 8 and provided with openings 17 which may be moved into register with the openings 15 or so adjusted as to completely cut off the flow of air from the chamber 4 into the tuyère boxes. 20 The partitions 14 of each frame form with the upper ends thereof high pressure air chambers whose bottoms are open and therefore in direct communication with the upper end of the air chamber 4 and these ends, 25 which form continuations of the side walls of the retort, have formed in them outwardly flaring passages 18 whereby air under relatively high pressure may be delivered directly into the fuel in the upper part 30 of the retort.

The otherwise open or top face of each of the stationary tuyère boxes is normally closed by an elongated, longitudinally reciprocable tuyère plate 19 whose lower end is 40 offset so as to rest upon the ledge 10 of one of the frames 8 and whose upper end is formed to slidably engage the flat face of the top 20 of the high pressure air chamber 21 at the upper end of each tuyère box. 45 Each of these tuyère plates has at opposite sides hooked lugs 22 extending under retaining or locking projections 23 on the side walls of the frames 8 so as to prevent them moving vertically while permitting their 50 free longitudinal movement. Each of said tuyère plates has formed in it a series of relatively narrow, vertically and rearwardly extending slots 24 constituting tuyère openings for the delivery of air from the tuyère 55 boxes and in addition there are air passages 25 in the top plate 20 which in certain positions of the tuyère plate, communicate with tuyère openings 26 and 27 therein.

For the purpose of longitudinally reciprocating each of the several tuyère plates I mount a lever 28 in the bottom of each of the frames or tuyère boxes 8 in such position that one arm thereof extends into a recess in a lug 29 projecting down from the under 60 side of the upper end of the tuyère plate.

while a second arm extends between the forks of an operating arm 30 fixed on a shaft 31 extending parallel with the line of the retort and periodically oscillated through an angle of 60°, for example, by any suitable mechanism (not shown). 70

With the above described arrangement of parts, air under pressure is delivered to the chamber 4 from a suitable source such as a blower or compressor and fuel is likewise fed into the retort 3 from one or both ends thereof so that it rises in said retort and flows down over the tuyère plates 19 on the opposite sides thereof. After the fuel has been ignited, the air under the relatively high 75 pressure at which it is delivered to the chamber 4, flows into the high pressure chambers 21 of the tuyère boxes and is delivered therefrom through the tuyère openings 18 into the retort and also through the 80 openings 25, 26 and 27, when tuyère plates 19 have been brought into the positions shown in Fig. 4. These plates are reciprocated on their supporting frames by oscillation of the shaft 31 and tend to cause movement of the fuel away from the retort downwardly toward and onto the dumping 85 plates 11.

The grid or valve plate 16 is so adjusted as to supply air at a relatively low pressure 90 to the main portions of the tuyère boxes and this air is delivered through the tuyère openings 24 into the fuel as said plates are reciprocated, thus insuring the complete burning of the fuel before it reaches the 95 dumping plates 11. It will be understood that the regulating valve or grid 16 is adjusted by any suitable means so as to regulate the amount of air delivered through the openings 24 to that required for the 100 proper combustion of the fuel. Owing to the shape and disposition of the tuyère openings 24 and to the outwardly flowing currents of air passing through them, there is no sifting of the finer particles of fuel or 105 ash into the tuyère boxes.

Moreover since the ledges 10 of the frames 8 are completely covered by the lower ends of the tuyère plates, the friction between these elements is reduced to a minimum, 110 since particles of fuel and ash are not likely to get between them. While the plates 19 have limited bearing on the vertical side members of the frames 8, frictional resistance due to particles of fuel getting between 115 these parts is relatively small and the same is true of the coating surfaces of the top portions 20 of the frames and the upper ends of the tuyère plates. The latter may be readily removed and replaced when this 120 is desirable for any purpose and they may be designed to suit the grade of fuel used in the stoker.

Owing to the possibility of accurately regulating the amount of air through the 125

low pressure chambers of the tuyère boxes, a minimum of air may be used, and the regulation may be such as to cause the complete consumption of the fuel. The structure as a whole is relatively simple and may be so constructed as to require a minimum of repairs.

From the above description it will be noted that it is not possible for the air delivered from the source of supply to take such a course as will permit or cause burning or overheating of the tuyère plates or of their supporting frames, but on the contrary the arrangement is such that these parts are maintained relatively cool and in operative condition.

I claim:

1. The combination in a stoker of a retort; a series of stationary air boxes extending at right angles to said retort; tuyère plates longitudinally slideable on the air boxes respectively; means for supplying air under pressure to the air boxes; and means for reciprocating the tuyère plates.
2. The combination in a stoker of a retort; a series of coating frames forming air boxes extending at right angles to said retort; a tuyère plate slidably mounted on each of the air boxes; means for reciprocating the tuyère plates toward and from the retort; and means for supplying air under pressure to the air boxes.
3. The combination in a stoker of a retort; a series of stationary air boxes extending at right angles to the retort; tuyère plates longitudinally slideable on the air boxes respectively; an air supply chamber; and means for controlling the flow of air from said chamber to the air boxes.
4. The combination in a stoker of a retort; a series of stationary air boxes extending at right angles to the retort; tuyère plates longitudinally slideable on the air boxes respectively; an air supply chamber; and means for controlling the flow of air from said chamber to the air boxes, consisting of a valve member extending in a line at right angles to the air boxes.
5. The combination in a stoker of a retort; an air supply chamber under the retort; a series of air boxes extending at right angles to the retort and having aligned openings respectively communicating with the air chamber; tuyère plates respectively slideable longitudinally on said air boxes; means for reciprocating said tuyère plates; and a valve member coacting with the openings of the air boxes and adjustable to govern the flow of air from the chamber thereto.
6. The combination in a stoker of a retort; a series of interlocked frames forming elongated air boxes extending in lines at right angles to said retort; tuyère plates slideably mounted on said boxes respectively and locked thereto against vertical move-

ment; means for reciprocating said tuyère plates on the air boxes; and means for supplying air under pressure to the air boxes.

7. The combination in a stoker of a series of frames of angular cross section coacting to form a series of open topped elongated air boxes; a retort extending transversely of the upper ends of said air boxes; tuyère plates mounted on the frames and forming tops for the same; with means for reciprocating said tuyère plates toward and from the retort.

8. The combination in a stoker of a retort; a series of air boxes extending at right angles to the retort and each having a transverse partition adjacent its upper end dividing it into two chambers; a tuyère plate slidably mounted on each of said air boxes; an air supply chamber normally communicating with both of the chambers of each of the air boxes; and a slideable valve member governing the flow of air from said chamber into one of the chambers of each of the boxes.

9. The combination in a stoker of a retort; a series of air boxes extending at right angles thereto and each having a partition dividing it into two chambers of which the smaller is adjacent the retort; an air supply chamber communicating with both chambers of each of the air boxes; a tuyère plate reciprocable on each of the air boxes and having air delivery openings; a valve member movable at right angles to the lines of the air boxes and formed to control the flow of air from the supply chamber to the larger chambers thereof; and means for reciprocating the tuyère plates.

10. The combination in a stoker of a retort; air boxes extending at right angles to said retort; a series of agitator tuyère plates slidably mounted on said boxes; an oscillatory shaft; and a series of levers for transmitting movement from said shaft to said agitator plates respectively.

11. The combination in a stoker of a retort; an air supply chamber under the same; an ash pit; a series of elongated air boxes extended at right angles from the retort over the ash pit; dumping plates at the lower ends of the air boxes; agitator tuyère plates mounted on the air boxes; and means for reciprocating said plates toward and from the retort.

12. The combination in a stoker of a retort; a series of air boxes made up of frames of L-shaped section; agitator tuyère plates slideable on the top edges of adjacent parts of said frames; and means for longitudinally reciprocating said plates.

13. The combination in a stoker of a retort; a series of elongated closed bottom stationary air boxes extending substantially at right angles to said retort; elongated perforated plates respectively closing the tops

130

of said boxes; means for supplying air under pressure to the boxes; and means for reciprocating the plates toward and from the retorts.

5 14. The combination in a stoker of a retort; a series of elongated closed bottom stationary air boxes extending substantially at right angles to said retort; elongated per-

forated plates respectively closing the tops of said boxes; means for supplying air under pressure to the boxes; means for reciprocating the plates toward and from the retorts; with a partition in each of the air boxes dividing it into two chambers of which one has openings into the retort.

PETER E. SMITH.
